MARSHMAN W. HAZEN, OF NEW YORK, N. Y., ASSIGNOR TO CORONA TYPEWRITER COMPANY, INCORPORATED, A CORPORATION OF NEW YORK.

LINE-SPACING MECHANISM.

1,121,096.

Specification of Letters Patent. Patented Dec. 15, 1914.

Original application filed June 23, 1908, Serial No. 439,967. Divided and this application filed June 3, 1909.
Serial No. 499,874.

To all whom it may concern:

Be it known that I, MARSHMAN W. HAZEN, a citizen of the United States, and a resident of New York, county and State of New York, have invented certain new and useful Improvements in Line-Spacing Mechanisms, of which the following is a full, clear, and exact description.

This invention relates more particularly to line-spacing means for visible typewriting machines, and is a division of my pending application Sr. No. 439,967, filed June 23, 1908.

The primary object of the invention is to provide simple and efficient means for line spacing the platen of typewriting machines and to positively lock and hold the platen in its shifted position in order that the spacing will be the same between all of the lines, and to provide simple means whereby the degree of spacing may be readily and quickly changed.

A further object of the invention is to provide means whereby the platen may be shifted independent of the line-spacing mechanism.

With these and other objects in view, the invention will be hereinafter more particularly described with reference to the accompanying drawings, which form a part of this specification, and will then be pointed out in the claims at the end of the description.

In the drawings, Figure 1 is a transverse section through one end of a carriage, taken on the line I—I of Fig. 2, showing in elevation one means for line-spacing the platen. Fig. 2 is a fragmentary front elevation of one end of the carriage and platen; and Fig. 3 is a fragmentary side elevation, partly broken away and partly in section, of the carriage and mechanism for line-spacing the platen, looking in a direction opposite to that shown in Fig. 1.

While the invention is more particularly adapted for visible typewriting machines in which the platen carriage is foldable forward into overhanging relation to the keyboard or otherwise moved into compact relation to another part of the machine to adapt the machine for transportation and other purposes, the said invention may be used in connection with typewriting and like machines of various kinds.

The carriage bed 10 or other support is suitably positioned with relation to other parts of the machine and is provided with a grooved bar 11 along one edge lengthwise thereof and with buttons or other engaging parts 12 along the other edge thereof. The bar 11 and the parts 12 are engaged by the carriage rails 13 and 14 respectively. These rails 13 and 14 are mounted upon the base 15 of a carriage 16. A platen 17 is held to rotate between the ends 18 of the carriage and said carriage is adapted to move lengthwise of the bed 10, the latter being slotted, as at 19, to permit a part of the escapement mechanism to pass therethrough to engage a part carried by the carriage in order that the carriage may be moved for letter spacing. The parts as thus described may be the same as in my pending application already referred to or of any preferred construction.

As a means for line-spacing and to prevent the platen from moving beyond a certain point no matter how rapidly the platen may be rotated, I provide a lever 20 which is pivotally held to the platen shaft 21 near one end thereof and which is forced by a curved spring 22 normally in a direction to force the same against the stop 22^a arranged on one of the ends 18 of the carriage.

A pawl or dog 23 is pivotally at 24 to the lever 20 and has a tooth or engaging part 24^a and a heel 24^b. This pawl is normally forced in one direction by a spring 25 carried by said lever 20, said spring being fastened at one end to said lever 20 and its other end passing through a projection 26 on the pawl. The tooth 24^a of the pawl is adapted to engage the teeth of a ratchet wheel 27 carried by the platen 17, the spring 25 tending normally to force the pawl in a direction to cause the tooth 24^a to engage the teeth of said ratchet wheel. The heel 24^b of the pawl when the lever 20 is in the position shown in Fig. 1, is engaged also by the stop 22^a and this causes the pawl to be moved on its pivot 24 against the tension of the spring 25 and to disengage the pawl tooth 24^a from the teeth of the ratchet wheel and to hold said tooth disengaged. As soon as the lever 20 is moved away from the stop 22^a this will carry the pawl 23 therewith, and by reason of the spring 25 will hold the heel of the pawl against the stop 22^a until the relative movement between the

pawl and the lever is such that the tooth 24^a will engage the teeth of the ratchet wheel. On further movement of the lever 20 the pawl being carried therewith will by its engagement with the ratchet wheel rotate the platen according to the movement of the lever 20.

A pin or projection 28 is carried by the pawl or dog 23 and extends on one side thereof so as to overlie one edge of the lever 20. This pin serves as a stop or lock for the line-spacing of the platen, the distance the latter is moved being determined by the position of the movable stop, abutment or device 29. The device 29 is substantially triangular in form and in the position shown in Figs. 1 and 3, the platen will be moved a distance corresponding to two lines or a double space at each movement 20 of the lever 20, the tooth 24^a of the pawl during the movement of said lever passing to one side of the device 29 until the pin 28 engages said device.

A spring 32 is fastened to the carriage 25 at one end and has its free end located adjacent to the device 29 so as to engage either of two sides thereof. By shifting the device 29 on its pivot so that its side 31 will be engaged by the spring 32, the lever 20 30 with the pawl 23 cannot move as great a distance as when in the position of the parts shown in the drawings before the pin 28 will engage the device 29, and consequently the platen will be moved only the distance 35 of a single space or one line, the said device 29 being provided with a thumb nut or head 33 by which the same may be rotated on its pivot 30. The pin or stop 28 by engaging the device 29 will positively stop 40 the shifting of the platen thus positively locking the pawl in the teeth of the ratchet wheel 27 and causing the platen to have all the lines exactly spaced, the pin 28 in this locking position being confined between the 45 device 29 and a notched part 34 of the lever 20.

The ratchet wheel 27 is normally held against movement in either direction by an arm 35. This arm is pivoted at 36 to the 50 platen carriage frame and is provided with a tooth or projection 37 at its inner end which is adapted to engage the teeth of the ratchet wheel 27, and said arm is normally forced in one direction by a spring 38 to 55 cause the tooth 37 to engage the teeth of the ratchet wheel.

The arm 35 is provided with a pin or projection 39 which may be engaged by a lever 40. This lever 40 is pivoted at 41 on 60 the outside of the carriage frame and is provided with recesses 42 and 43 at its lower end. The recesses are at different distances from the pivot 41 so that when the lever is shifted to permit the recess 43 to engage 65 the pin 39, the tooth 37 will be held away

from the teeth of the ratchet wheel 27, as shown in the figures, to permit the platen to be rotated freely in either direction, but when said lever is in a position to permit the pin 39 to enter the recess 42 the tooth 70 37 in this case will engage the teeth of said ratchet wheel thus tending to hold the platen against movement. The pin 39 projects outward from the arm 35 through a slot 44 in one of the ends 18 of the carriage 75 frame to permit the said pin to be engaged by the end of the lever 40.

From the foregoing, it will be seen that simple and efficient means is provided whereby the platen may be rotated for line-spacing, and during such rotation the platen may be positively held and locked in order that the movement of the platen may be positive and each space correspond to the one preceding; that simple means is provided whereby the degree of spacing may be changed; and that simple means is provided whereby the platen may be rotated in either direction independent of the line-spacing mechanism.

Having thus described my invention, I claim as new and desire to secure by Letters Patent:—

1. In a typewriting machine, the combination with a support, of a platen mounted on the support, a ratchet wheel movable with the platen, a pivotally held line-spacing lever provided with a notched edge, a spring-retained pawl carried by the line-spacing lever, a device for limiting the movement of the lever, and a projection on the pawl adapted to engage the device and the notched part of the lever for governing the movement of said lever.

2. In a typewriting machine, the combination with a support, of a platen mounted on the support, a ratchet wheel movable with the platen, a pivotally held line-spacing lever axially arranged with respect to the platen, a spring-retained pawl carried by the line-spacing lever, a device for limiting the movement of the lever, and a projection on the pawl adapted to engage the device and a part of the lever for governing the movement of said lever and to hold the pawl in engagement with the teeth of the ratchet wheel.

3. In a typewriting machine, the combination with a support, of a platen mounted on the support, a ratchet wheel movable with the platen, a line-spacing lever, a pawl carried by the lever, a stop engaged by both the lever and the pawl, an abutment, and a projection on the pawl adapted to engage the abutment and the edge of the lever for limiting the movement of said lever.

4. In a typewriting machine, the combination with a support, of a pivoted line-spacing lever provided with a notched edge, a spring for forcing the lever in one direc- 130

tion, a pawl movable with the lever, a ratchet wheel adapted to be engaged by said pawl, a rotary device having a plurality of sides arranged in the path of movement of the pawl, a spring normally holding the rotary device in different positions, and a pin carried by the pawl adapted to engage said device and the notched part of the lever whereby different movements of the line-spacing lever may be obtained and relatively different rotary movements given to the platen.

5. In a typewriting machine, the combination with a support, of a pivoted line-spacing lever, a spring for forcing the lever in one direction, a pawl movable with the lever, a ratchet wheel adapted to be engaged by said pawl, a rotary device having a plurality of sides arranged in the path of movement of the pawl, a spring normally holding the rotary device in different positions, and a pin carried by the pawl adapted to engage said device and a part of the lever whereby different movements of said lever may be obtained and relatively different rotary movements given to the platen.

6. In a typewriting machine, the combination with a support, of a movable line-spacing lever, a pawl movable with the lever, a ratchet wheel adapted to be engaged by said pawl, means for forcing the lever in one direction, an abutment arranged in the path of movement of the lever, and a pin movable with the pawl adapted to engage said abutment and the edge of the lever to be locked between the same.

7. In a typewriting machine, the combination with a support, of a movable line-spacing lever, means for forcing the lever in one direction, a movable device arranged in the path of movement of the spacing lever adapted to vary the throw thereof, a ratchet wheel, a pawl adapted to engage said wheel and pivoted on and movable with the lever, a stop adapted to be engaged by both the lever and pawl, and means carried by the pawl adapted to engage the movable device and the lever for limiting the movement of said lever.

8. In a typewriting machine, the combination of a carriage, a platen mounted on the carriage, a ratchet wheel movable with the platen, an operating lever pivotally held concentric to the axis of said wheel, a pawl carried by said lever, an adjustable abutment, and a projection carried by the pawl and adapted to engage the abutment and to be positively locked between said lever and the abutment at the end of the movement of the lever.

9. In a typewriting machine, the combination with a support, of a carriage mounted on said support, a line-spacing lever pivotally held to the axis of the platen, means for forcing the lever in one direction, a pawl

movable with the lever, a ratchet wheel adapted to be engaged by said pawl, a rotary substantially triangular abutment arranged in the path of movement of the pawl, a spring normally holding the abutment in different positions by engagement with the sides, and means carried by the pawl adapted to engage said abutment whereby different movements of the lever may be obtained and relatively different rotary movements given to the platen.

10. In a typewriting machine, the combination with a support, of a carriage mounted on said support, a lever mounted on the carriage, means for forcing the lever in one direction, a pawl movable with the lever, a ratchet engaged by said pawl, a stop adapted to be engaged by both the lever and pawl, an adjustable abutment arranged in the path of movement of the lever, and means carried by the pawl adapted to engage said abutment and be locked between said lever and the abutment.

11. In a typewriting machine, the combination of a carriage, a line-spacing lever mounted on the carriage, a ratchet wheel, a pawl carried by the lever and adapted to engage the ratchet wheel, means adapted to positively disengage the pawl from the ratchet wheel, an abutment arranged in the path of said lever and to limit the movement thereof and to hold the pawl in engagement with the teeth of the ratchet wheel, and means whereby the pawl may be positively held between the abutment and the lever at the end of its movement.

12. In a typewriting machine, the combination of a carriage, a platen mounted on said carriage, a ratchet wheel carried by the platen, a horizontally arranged arm pivotally held at the inner side of one end of the carriage and having a tooth adapted to normally engage the teeth of the ratchet wheel, said lever having a part projecting through to the outside of the carriage, a hand lever pivotally held to the carriage frame on the outside thereof and having a cam-acting end adapted to engage the projecting part of said arm to release the tooth to permit the platen to be moved to any desired position.

13. In a typewriting machine, the combination of a carriage having upward extending end plates one of which has a slot, of a platen mounted on said carriage, a ratchet wheel movable with the platen, an arm pivotally held to the carriage on the inner side of one end and having a pin projecting through said slot in the end of the carriage, said arm having means to engage the teeth of the ratchet wheel to prevent movement of the platen except in one direction, a spring normally forcing the arm in one direction, a lever pivotally held to the carriage on the outside of one end thereof and

having a recess at one end forming a seat for said pin and so positioned as to release the arm when moved in one direction to permit the platen to be moved freely in the carriage.

14. In a typewriting machine, the combination of a carriage having end plates, a platen mounted on said carriage one end of which has a slot therethrough, a ratchet wheel carried by the platen, a horizontally arranged arm pivotally held to the carriage on the inner surface of one end and adapted to normally engage the teeth of the ratchet wheel to prevent movement of the platen except in one direction, said arm having a pin projecting through said slot, a lever pivotally held to the carriage on the outside of one end thereof and adapted to engage a part of the pin of said arm to release and hold the arm disengaged to permit the platen to be moved in any direction.

15. In a typewriting machine, the combination with a support, of a line-spacing lever pivotally held to the axis of the platen, a spring for forcing the lever in one direction, a pawl movable with the lever, a rotary device having a plurality of sides arranged in the path of movement of the pawl, a spring normally holding the device in

different positions, means carried by the pawl adapted to engage said device whereby different movements of the line-spacing lever may be obtained and relatively different rotary movements given to the platen, and a pin carried by the support for automatically releasing the pawl when said lever is in its normal position.

16. In a typewriting machine, the combination with a support, of a carriage mounted on said support, a line-spacing lever mounted on the carriage, means for forcing the lever in one direction, a ratchet wheel, a pawl carried by the lever, a movable device having a plurality of sides arranged in the path of movement of the spacing lever, a pin movable with the lever adapted to engage said device and be confined between the same and said lever, and a pin located on the support adapted to automatically release the pawl when in its normal position.

This specification signed and witnessed this 29th day of May A. D. 1909.

MARSHMAN W. HAZEN.
